(57) CLAIM

The ornamental design for a shoe, as shown and described.

DESCRIPTION

1. Shoe

1.1 : Perspective

1.2 : Front

1.3 : Back

1.4 : Left

1.5 : Right

1.6 : Top

1.7 : Bottom

1.8 : Perspective Bottom View

The drawings only show the design on the left shoe, the right shoe is omitted as it is symmetrical to the left shoe.

The stitching shown on the shoe upper forms a part of the claim.
